STRUCTURAL UNIT

Walter C. Voss, Wellesley, Mass.

Application May 3, 1935, Serial No. 19,725

3 Claims. (Cl. 20—6)

This invention relates to structural units and, more particularly to a floor, ceiling, roof or wall unit which lends itself readily to mass assembly and which will be strong, durable and rigid.

5 An important object of the invention is the provision in a construction of this type of an arrangement permitting the statics of arch construction to be employed as the basic strength of the unit.

10 A further and more specific object of the invention is the provision of a floor, ceiling, roof or wall unit which provides for the ready incorporation of an arch construction rendering the same very rigid and which is of such form 15 that it may be readily modified to enable its use in the structures requiring the supports of loads of considerable magnitude.

20 A further object of the invention is the provision in a construction of this character of an arrangement such that sound-proofing or heat insulation may be readily made a factor of the construction.

25 These and other objects I attain by the construction illustrated by the accompanying drawings wherein, for the purpose of illustration, I have shown a preferred embodiment of my invention and wherein:

Fig. 1 is a plan view of a structural unit constructed in accordance with my invention;

30 Fig. 2 is a longitudinal sectional view there-through on line 2—2 of Fig. 1;

Fig. 3 is a transverse sectional view on line 3—3 of Fig. 2;

35 Fig. 4 is a fragmentary detail sectional view showing a modified method of retaining the arch means in its flexed form;

Fig. 5 is an enlarged fragmentary sectional view of a construction such as shown in Figs. 1 to 3;

40 Fig. 6 is a similar view showing a slightly modified construction;

Fig. 7 is a section on line 7—7 of Fig. 6;

Fig. 8 is a vertical section illustrating a preferred construction of wall unit; and

45 Fig. 9 is a fragmentary longitudinal sectional view illustrating a modified unit construction for use in fireproofing.

Referring now more particularly to the drawings, the unit generally designated at 10 may 50 be made in any suitable size and shape and comprises broadly an arch means 11 consisting of one or more flexible and elastic sheets, the ends of which preferably bear against thrust elements 12. The flexible and elastic sheet means 55 is retained in its arched form and secured against

warping by means of longitudinally-extending ribs 13 which have form-retaining engagement therewith. Such engagement may be accomplished either by forming the ribs in two sections 13a and 13b, between which a unitary sheet means is fastened or by forming the flexible sheet means in a plurality of sections 11a, 11b, while constructing the ribs as solid units shown at 13c in Fig. 4. The edges of the sections of the flexible sheet means will have engagement with the ribs preventing their deflection from their normal or desired form, this engagement being at present shown as provided by grooving the sides of the ribs 13c as at 14 to admit the edges of the sections 11a, 11b. Obviously, the grooves to receive the edges of these sections may be provided by an applied structure if so desired. Where the ribs are formed in a plurality of sections, suitable means is provided for retaining these sections in clamping relation with the flexible sheet means 11. An example of this structure is specifically shown in Figs. 2—3, wherein each of the sections 13a, 13b of the ribs is engaged by a saddle 15, the saddle having projecting ears 16 which connect by bolts 17 passing through the flexible sheet means. The arrangement of the ribs 13 is preferably such that these ribs will form longitudinal side walls for the completed unit. The ribs whether of unitary or sectional construction may, if so desired, be lightened by perforating the same as suggested in Fig. 2 at 18.

In Figs. 6 and 7, I have shown a slight modification of the rib structure wherein the rib means comprises simply an overlying member 13d having its under surface properly contoured to engage against the arch and to which the arch is secured as indicated at 11c. With this construction, a straight stringer S may be employed beneath the arch and will function to lighten the construction similarly to the perforations suggested in Fig. 6.

The thrust elements 12, against which the ends of the arch bear, are suitably connected by tension means generally designated at 19. This tension means may comprise either a panel 20, which serves to close the bottom face of the unit or, in event it is desired that the closure for the bottom face of the unit consist of material unsuitable as a tension means, then auxiliary tension means may be provided, as for example wires 21 in Figs. 6 and 7. The ribs 13 may comprise or assist in the formation of the tensioning means, being connected to the thrust elements 12 by shear plates 24 which are bolted 55

or otherwise secured to the ribs and have flanges 25 secured to the thrust elements. End walls 22 for the unit may be connected with these thrust elements, these end walls, together with the upper surface of the ribs, providing seats for a top closure panel 23. It will be obvious that the panels 20, 23, end walls 22 and ribs 13 will combine to provide above and below the arch, chambers which may be filled with heat 10 or sound-proofing material as desired.

In Fig. 8 I have illustrated a form of construction of the unit particularly adaptable for use in wall construction. This construction, as illustrated, includes two oppositely flexed sheets 11d 15 bearing against identical thrust element 12d. As shown, duplicate intermediate ribs 13e are employed, separated at their confronting edges by an intermediate panel P. This panel may be omitted if so desired and the ribs 13e formed 20 integrally.

In Fig. 9 I have shown a form of floor or ceiling unit adapted for use in fireproof construction wherein the upper rib has been omitted and a porous filling F substituted therefor. This 25 filling may be any of the standard light-weight porous filling materials utilized for fireproofing purposes.

The construction as illustrated is obviously capable of considerable modification without in any 30 manner departing from the spirit of my invention and I do not wish to be understood as limiting myself thereto excepting as hereinafter claimed.

I claim:

35 1. A structural unit comprising a normally flat flexible elastic sheet means of structural material capable of taking compressive stresses sprung to form an arch, thrust elements against which the ends of the sheet bear, longitudinally-extending ribs maintaining the sheet in its sprung form and affording seats for a panel, a panel secured to said seats, and means to limit 40 separation of the thrust elements.

2. A structural unit comprising a normally flat flexible elastic sheet means of structural material capable of taking compressive stresses sprung to form an arch, thrust elements against which the ends of the sheet bear, longitudinally-extending ribs maintaining the sheet in its sprung form and affording seats for a panel, and a panel secured to said seats, said panel comprising a tension element limiting separation of said thrust elements. 5

3. A device as claimed in claim 1 wherein the ribs include upper and lower sections between which the sheet means is clamped. 10

4. A device as claimed in claim 1 wherein the sheet means is formed in sections separated by said ribs and the edges of said sections have a form-retaining connection with the ribs. 15

5. The structure of claim 1 wherein the ribs have means limiting separation of the thrust elements. 20

6. A structural unit comprising a hollow parallelopiped, normally flat elastic sheet means of structural material capable of taking compressive stresses flexed to form an arch within the unit and having thrust engagement at its ends with opposed walls thereof, and means within the unit to prevent variation of the arch form and to support the walls of the unit which flatly oppose the arch. 25

7. A device as set forth in claim 2, wherein the ribs overlie the arch and have their lower surfaces contoured to fit thereagainst and the arch is secured to the ribs. 30

8. A structural unit comprising normally flat flexible elastic sheet means of structural material capable of taking compressive stresses sprung to form oppositely bowed arches, thrust elements against which the ends of these sheets bear, longitudinally-extending ribs maintaining the sheets in their sprung form and affording seats for a panel, and a panel secured to said seats. 35
